UNITED STATES PATENT OFFICE.

PAUL M. HOTCHKIN, OF CHICAGO, ILLINOIS, ASSIGNOR TO NATIONAL X-RAY
REFLECTOR COMPANY, A CORPORATION OF ILLINOIS.

DESIGN FOR A BRACKET FOR REFLECTORS.

42,580.

Specification for Design.

Patented June 4, 1912.

Application filed December 12, 1911. Serial No. 665,403. Term of patent 7 years.

To all whom it may concern:

Be it known that I, PAUL M. HOTCHKIN, a citizen of the United States, residing at Chicago, in the county of Cook and State of Illinois, have invented a new, original, and ornamental Design for a Bracket for Reflectors, of which the following is a specification, reference being had to the accompanying drawing, forming part thereof.

The figure is a perspective view, showing my new design.

I claim:

The ornamental design for bracket for reflectors, as shown.

PAUL M. HOTCHKIN.

Witnesses:

M. M. HEDDEN,
M. M. BOHAN.
